UNITED STATES PATENT OFFICE.

OTTO EPPENSTEIN, OF JENA, GERMANY, ASSIGNOR, BY MESNE ASSIGNMENTS, TO BAUSCH & LOMB OPTICAL COMPANY, OF ROCHESTER, NEW YORK, A CORPORATION OF NEW YORK.

TELEMETER.

Application filed August 13, 1921, Serial No. 492,107, and in Germany July 21, 1919.

(GRANTED UNDER THE PROVISIONS OF THE ACT OF MARCH 3, 1921, 41 STAT. L., 1313.)

The invention relates to telemeters of the well-known, usual construction with the base-line in the instrument and having two telescope systems with their objective axes lying 5 in the base-line, in front of each of which, at the corresponding end of the base-line, a reflecting system is disposed, which is non-sensitive to slight rotations in the plane of measurement, deflects the entering pencils 10 of rays by 90° in the plane of measurement and leads them directly to the corresponding telescope system. The other component parts of these telemeters, such as the separating prism system, the ocular arrangement, 15 the measuring device etc., are of no importance as regards the invention and can be of any desired construction. Every telemeter of this type requires, as is well known, to have its indicating arrangement corrected 20 from time to time, as it is impossible in practice to keep the separate component parts of the latter and their relative position entirely invariable. The correction of such telemeters has usually been effected 25 heretofore with the aid of a correcting lath or some equivalent means, which makes it possible to present two marks to the telemeter, which correspond to an infinitely distant object, so that after setting the telemeter 30 to these marks the indicating device can be caused to read infinity and the telemeter can be thus corrected. Another known method consists in placing an auxiliary reflecting system in front of the telemeter, by which the base-line of the instrument 35 can be temporarily brought to the zero value, so that any object (not too near in practice) must give the reading infinity in the telemeter and a rectification of the indicating device by it is possible. Thereby, in 40 the present case as well as throughout the following the "base-line of the value zero" signifies that the base-line has the value zero in the direction which is essential for measuring. The chief drawback of both methods is, that the correcting lath or the corresponding auxiliary arrangement must always be carried along with the instrument. Further 45 it has become known through Patent 1,085, 50 883, to give the telemeter temporarily the base-line zero by a suitable change over of the reflecting systems used in the telemeter itself, and then to correct the reading infinity again with the aid of any distant object. As explained in the said patent, the condition must be fulfilled, that, on the reflecting systems being changed over, the total error 55 of reflection shall not change its value as regards magnitude and sign. The said patent deals however, throughout with forms 60 of telemeters, which deviate from the form defined at the beginning of this and have mostly a considerably more complicated arrangement. The object of the invention 65 consists in giving telemeters of the above mentioned simple form temporarily the base-line zero without the employment of further auxiliary means, using only the two reflecting systems already provided in the telemeter, so as to be able at any time to carry 70 out a correction with the aid of any distant object. For this purpose the two reflecting systems, which are located at the ends of the base-line, are so formed and disposed, while preserving the non-sensitivity to slight rotations 75 in the plane of measurement, that for the correction one of the reflecting systems can be placed unchanged in front of the entrance opening of the stationary second reflecting system and a base-line of the value 80 zero is thereby brought about. Thus, after one of the reflecting systems has been changed over into the correcting arrangement, the pencils of rays coming from any distant object enter directly into one of the 85 telescope systems in the direction of the original base-line, while they reach the other telescope system after passing through both reflecting systems, being thus deflected twice 90 through 90° in the plane of measurement. 95 The total error of reflection, which may have been present in the measuring device, remains the same in the correcting position as well, as only the possible error of reflection of the reflecting system that can be changed over, which was previously effective only on one side, is now transferred unaltered as to magnitude and sign to the other side and is added directly to the error of reflection of the second reflecting system. 100 As both telescope objectives lie with their axes in the base-line, a slight displacement in the vertical direction is required for the pencils of rays, which in the correcting position have to pass through both reflecting 105 systems, in order to transmit them above or

below the telescope systems to the other side of the telemeter. This slight displacement in the vertical direction, which can be effected by one reflecting system 5 only or by both, partially by each, can of course not be avoided in the measuring position, so that the pencils of rays coming from the object to be measured do not enter accurately in the same horizontal plane into the telemeter, but only pass 10 into the plane of measurement containing the base-line, after passing through the reflecting systems. In practice this slight displacement in the height direction is known 15 to be of little importance.

Reflecting systems having the properties enumerated may be built up in various ways. A simple constructional form of the invention is obtained by using a reflecting system 20 known of itself, which is composed of two right-angled reflecting prisms, a larger one, in which the two cathetral surfaces act as reflecting surfaces, and a second prism of half the size, in which the hypotenusal surface is used as the reflecting surface. The two prisms are arranged in the same way as a Porro prism system, the last reflecting surface of which has been removed, so that such a system can be termed a three-quarter 25 Porro system. This system may also be imagined as having been derived from one reflecting surface of an optical square with a deflection of 90° being replaced by a ridge surface, the axial ray not being allowed to 30 impinge on the ridge itself but being displaced perpendicular to the ridge. Consequently this system has the property, just like an optical square, of being non-sensitive 35 to small rotations in the plane of deflection. 0 Such a reflecting system on one side of the base-line in combination with a second reflecting system like it or an ordinary optical square on the other side of the base-line, make a number of arrangements possible, 5 which correspond to the invention. Ordinary optical squares may also be used on both sides of the base-line, but in this case, as, when opposing the two optical squares, the 10 distance apart of the axial rays corresponding to their dimensions is retained, a pair of parallel reflectors facing each other must be used in addition, which displaces the axial ray corresponding to the base-line zero laterally by this amount and at the same time effects 15 the above mentioned displacement in the vertical direction. This pair of parallel reflectors can be combined in a suitable manner with one of the optical squares. In the 20 case of such an arrangement the number of reflecting surfaces is greater by one as compared with the first named constructional forms at least in one of the two reflecting systems. If a still greater number of reflecting surfaces be admitted, if for instance 25 one of the reflecting surfaces be replaced by

a ridge surface, further constructional forms may be derived without difficulty. In every case it remains fundamentally immaterial, which of the two reflecting systems is arranged so as to be changed over. For practical reasons as a rule the simpler one will be used for this purpose. Similarly it is immaterial as regards the essence of the invention, whether the reflecting systems be embodied by actual reflectors or combined 70 from reflecting prisms. For the practical construction of a telemeter according to the invention the change-over system will be combined with a casing or a mount, for which, both in the measuring position and 75 in the correcting position, suitable guides and stops are provided on the casing of the telemeter, so that the reflecting system may be conveniently and quickly changed over. 80

The idea of placing one reflecting system 85 in front of the other in a telemeter, which is provided at both ends of the base-line with three-quarter Porro systems, for correcting purposes, has already been mentioned in the British Patent 18273 of the year 1902. The 90 possibility of thereby obtaining the base-line zero and of thus being able to correct the telemeter at any time without auxiliary means is however not present in consequence of the quite different general arrangement. 95 On the contrary it is pointed out that a small base-line still remaining after the change-over can only be brought to the value zero, by employing special auxiliary means, namely a rhombic reflecting prism. This rhombic 100 prism on its part also suffers from a reflecting error, which must be taken into account and therefore requires an adjustment in two different positions, so that a considerably more complicated method of correction 105 results than with the telemeter according to the invention.

In the annexed drawing the invention is 110 illustrated by a number of different constructional forms in a diagrammatic manner. Each constructional form is shown by an elevation and a plan view drawn below it. Figs. 1 and 2 show the first example, Figs. 3 and 4 the second example, Figs. 5 and 6 the third example, Figs. 7 and 8 the fourth example, Figs. 9 and 10 the fifth example, 115 Figs. 11 to 13 the sixth example, Figs. 14 to 16 the seventh example. The parts of the telemeter that are of no importance for the invention are uniformly indicated in all 120 the examples, the two telescope objectives lying with their axes in the base-line by two lenses a^1 and a^2 , the separating prism system by two crossed reflectors b^1 and b^2 , the ocular system by a lens c and the measuring arrangement by a refracting prism d , 125 which is displaceable in the direction of the base line. Of the two reflecting systems at the ends of the base-line the left hand one is always assumed to be the stationary one 130

and the right hand one the one to be changed over; in each case the latter is shown in dotted lines in the changed over position, i. e. the correcting position. Of course in 5 every case the two reflecting systems may change place.

Figs. 1 and 2 show a telemeter, which has as stationary reflecting system a three-quarter Porro system e^1 and as change over system 10 a pentagonal prism e^2 . The Porro system e^1 , which displaces the pencils of rays entering on the left hand side of the telemeter downwardly by a small amount, is so disposed that the pentagonal prism e^2 , after 15 a rotation of 180° in the plane of measurement, can be brought simply in front of the entrance aperture of the Porro system e^1 and the base-line zero thus produced. For 20 this purpose the parts of the telemeter, serving the entrance of the rays, are constructed in the following manner. The two ends of a tubular casing m , carrying the telescope systems are carried out as prism heads which 25 are denoted by n^1 and n^2 . The prism head n^1 is closed on the side facing the observer by a lid o and contains the three-quarter Porro system e^1 , whose position is secured by gripping jaws p^1 and p^2 and screws q^1 and q^2 . The prism head n^2 is provided 30 with an aperture n^3 , which lies in the optical telescope axis and through which the light enters the telescope objective a^2 during the correcting process. It comprises a prism casing r , containing the pentagonal prism e^2 35 and closed by a lid r^1 which casing is fixed by fine screws s^1 , s^2 , s^3 , s^4 and s^5 . After loosening these screws the prism casing r can be drawn out from the prism head n^2 and 40 inserted into the prism head n^1 , having a corresponding opening n^4 , in the position required for the correction. The prism e^2 is fixed in the prism casing r by a screw t by means of a gripping jaw u and by a spring 45 v fixed on the lid r^1 .

In the example shown in Figs. 3 and 4 inversely the stationary reflecting system is embodied by a pentagonal prism f^1 and the change over reflecting system by a three-quarter Porro system f^2 . For bringing the 50 change-over reflecting system f^2 into the correcting position in this case a rotation in the base-line through 180° is first necessary and thereupon a rotation in the plane of measurement through 90° .

The telemeter shown in Figs. 5 and 6 has at both ends of the base-line three-quarter Porro systems g^1 and g^2 respectively, these two systems being exactly similar, so that the entering pencils of rays are displaced downwards on one side and upwards on the other side by the same amount. For producing the correcting arrangement the same alteration in position of the right hand reflecting system g^2 is required as in 60 the example according to Figs. 3 and 4.

In the constructional form shown by Figs. 7 and 8 two Porro systems h^1 and h^2 , which are symmetrical to the Porro system of the former example, are used, the right hand reflecting system h^2 being somewhat differently arranged so that for bringing about 70 the correcting position only a rotation through 180° in the plane of measurement is required.

The arrangement according to Figs. 9 75 and 10 also has two three-quarter Porro systems, two slightly different forms however, viz on the right hand side the system i^2 , which is symmetrical to the Porro system of the example Figs. 5 and 6, on the left hand side on the other hand a Porro system i^1 with a displacement of the pencils of rays in the vertical direction, which is twice as great and equally directed. Thereby, as 80 is seen from the figures, the total displacement of the entering pencils of rays relatively to each other may be reduced both in the measuring position and in the correcting position to half the amount of the two former examples. In this case as well for 85 the correcting position the same alteration of position of the change-over system i^2 is to be effected as in the example according to Figs. 5 and 6.

Figs. 11 and 12 show a constructional example, in which on both sides of the base-line optical squares in the form of pentagonal prisms k^1 and k^2 are used, the change-over prism k^2 however being firmly cemented to a rhombic prism k^3 , which 90 brings about the requisite displacement of the axial ray, which enters in the correcting position with the base-line zero. Fig. 13 shows this cemented reflecting system k^2 , k^3 in side elevation. When changing over to 105 the correcting position, the right hand reflecting system k^2 , k^3 must be rotated through 180° in the plane of measurement.

The last constructional example, Figs. 14 110 to 16, also has optical squares at both ends of the base-line, the change-over system being a simple pentagonal prism l^4 , while the stationary system is an optical square, which, for effecting the required displacement of the pencils of rays, is cemented together out of two parts l^1 and l^3 with an interposed rhombic prism l^2 . Fig. 16 shows a side elevation of this system l^1 , l^2 , l^3 . In this case as well for passing to the correcting position a rotation of the pentagonal prism l^4 through 180° in the plane of measurement is necessary.

I claim:

1. In a telemeter two telescope systems with their objective axes lying in the base-line of the instrument, two reflecting systems, each of which being adapted to deflect the rays entering it by 90° , one of these reflecting systems being fixed in front of one of the said telescope systems, and means 125

for fitting the other reflecting system alternately in front of the other telescope and, rotated by 180° in the plane of measurement, in front of the said reflecting system 5 in such a position that in this case the two telescope systems are directed to points lying in the same plane perpendicular to the plane of measurement.

2. In a telemeter two telescope systems 10 with their objective axes lying in the baseline of the instrument, two reflecting systems, each of which being adapted to deflect the rays entering it by 90°, at least one

of these reflecting systems being a three-quarter Porro system, one of these reflecting systems being fixed in front of one of the said telescope systems, and means for fitting the other reflecting system alternately in front of the other telescope and, rotated by 180° in the plane of measurement, in front of the said reflecting system in such a position that in this case the two telescope systems are directed to points lying in the same plane perpendicular to the plane of measurement. 15 20

OTTO EPPENSTEIN.
